UNITED STATES PATENT OFFICE

144,472

DESIGN FOR A CLOTHESPIN

William J. Ward, Kansas City, Mo.

Application November 23, 1945, Serial No. 123,985

Term of patent 14 years

(Cl. D17—6)

To all whom it may concern:

Be it known that I, William J. Ward, a citizen of the United States, residing at Kansas City, county of Jackson, State of Missouri, have invented a new, original, and ornamental Design for a Clothespin, of which the following is a specification, reference being had to the accompanying drawing, forming part thereof, in which

Fig. 1 is a top plan view of a clothespin embodying my new design,

Fig. 2 is a side elevational view,
Fig. 3 is a bottom plan view,
Fig. 4 is a rear elevational view, and
Fig. 5 is a front elevational view.

I claim:

The ornamental design for a clothespin, substantially as shown.

WILLIAM J. WARD.
